Ignatius Lucas.

UNITED STATES PATENT OFFICE.

IGNATIUS LUCAS, OF PASSAIC, NEW JERSEY.

ERASING INSTRUMENT.

No. 895,097.

Specification of Letters Patent.

Patented Aug. 4, 1908.

Application filed August 1, 1907. Serial No. 386,608.

To all whom it may concern:

Be it known that I, IGNATIUS LUCAS, a citizen of the United States, residing at Passaic, in the county of Passaic and State of New Jersey, have invented a new and useful Erasing Instrument, of which the following is a specification.

The objects of my invention are, first, to place the cutting edges of an erasing instrument in positions whereby all danger of one cutting himself or others while handling the said erasing instrument is avoided; second, to make the sharpening of the erasing instrument a simple operation.

I attain these objects by the mechanism illustrated in the accompanying drawing in which—

Figure 1 is a perspective view of the erasing instrument. Fig. 2 is a perspective view of a modification of the erasing instrument. Fig. 3 is a perspective view of the erasing instrument held on a grindstone as in the act of sharpening the erasing instrument. Fig. 4 is a perspective view of the modified erasing instrument held on a grindstone as in the act of sharpening the said modified erasing instrument. Fig. 5 is a bottom view of the erasing instrument. Fig. 6 is a side view of the modified erasing instrument. Fig. 7 is a top or bottom view of the modified erasing instrument.

A handle A, Fig. 1 has at its end a head B. The wall C, of this head B, declines inward from the neck D, to the apex E, in a straight line as shown in Fig. 5. The wall C, is also curved from the neck D, to the apex E, shown in Fig. 1 and Fig. 3.

In Fig. 3 is shown how the cutting edge of the wall C, of the head B, lays all over in a

plane on a grindstone or other sharpening implement as in the act of sharpening the cutting edge of the erasing instrument.

The apex E, Fig. 1 of the erasing instrument is blunt.

In Figs. 2, 4, 6, 7, views of a modified form of the erasing instrument show the head B', with two previously described walls C', joined at the apex E'.

I claim:

1. The erasing instrument comprising a handle at an end of which is a steel head the walls of which forming the cutting edges decline in a straight line inward from the neck to the apex of the head, when viewed from top or bottom.

2. The erasing instrument comprising a handle at an end of which is a steel head the walls of which forming the cutting edges decline in a straight line inward from the neck to the apex of the head, when viewed from top or bottom, said head of said erasing instrument having the above described walls curved, when viewed from the side.

3. The erasing instrument comprising a handle at an end of which is a steel head the walls of which forming the cutting edges decline in a straight line inward from the neck to the apex of the head, when viewed from top or bottom, said head of said erasing instrument having the above described walls curved, when viewed from the side, the said walls of the said erasing instrument having a blunt point at the apex of the head.

IGNATIUS LUCAS.
